UNITED STATES PATENT OFFICE.

ALBERT GERSTENDÖRFER, OF NEW YORK, N. Y., ASSIGNOR TO GERSTENDÖRFER BROTHERS, OF SAME PLACE.

HYDRAULIC MOTOR.

SPECIFICATION forming part of Letters Patent No. 538,906, dated May 7, 1895.

Application filed November 8, 1894. Serial No. 528,185. (No model.)

To all whom it may concern:

Be it known that I, ALBERT GERSTENDÖRFER, a citizen of the United States, residing in the city, county, and State of New York, 5 have invented certain new and useful Improvements in Hydraulic Motors, of which the following is a specification.

This invention relates to an improved hydraulic motor for converting the force which is exerted by an outflowing column of water on a plug, piston, or valve that is arranged above the outlet-opening, into reciprocating motion; and the invention consists of a tank for containing water, provided with one or 15 more outlet-openings and discharge-pipes below said openings, a supply-pipe for said tank, a spring supported above the tank, and a piston or pistons suspended from said spring and arranged above the outlet-opening or 20 openings, so that by the alternate suction on the piston or pistons a downward pull is exerted on the spring so that the pistons will close the outlet-openings and permit the return motion of the spring so that the same is 25 reciprocated, the reciprocating motion being capable of conversion into continuous rotary motion, as will be fully described hereinafter and finally set forth in the claims.

In the accompanying drawings, Figure 1 30 represents a vertical longitudinal section of my improved hydraulic motor. Fig. 2 is a vertical transverse section of the same on line 2 2, Fig. 1, showing the same arranged with two pistons and two outlet-pipes; and 35 Fig. 3 is a vertical longitudinal section of a modified construction of the motor.

Similar letters of reference indicate corresponding parts.

In the drawings, A represents a tank of 40 suitable size and construction, which is provided with one or more outlet-openings a in its bottom and with outlet-pipes a' a' that discharge the water from the tank to a suitable discharge-pipe. The outlet-opening a' may 45 be provided with an S-shaped trap, or with a contracted portion, or with any other device used for obtaining a partial vacuum in the outflow pipe. Above the top of the tank is arranged a spring-bar B, which is either supported at both ends by suitable means at- 50 tached to the side-walls of the tank, as shown

in Fig. 1, or at one end, in which case the free end is capable of a vertical play. To this spring-bar B is attached, by means of a connecting-rod C', one or more plugs, pistons or 55 valves C, which are located at a definite distance above the outlet-openings in the bottom of the tank. When the spring-bar B is supported at both ends, and a plurality of pistons C used, the latter are connected by rods 60 C' with a transverse rod C² attached to the center of the spring-bar B, said spring-bar being connected by a pitman with a crank-shaft supported in suitable bearings above the tank, and which crank-shaft is provided 65 with a fly-wheel and suitable transmitting-mechanism, so that the reciprocating motion of the spring-bar is converted into continuous rotary motion. When the spring-bar B is supported at one end, the motion-transmitting 70 mechanism is applied to its outer free end, as shown in Fig. 3.

A supply-pipe E supplies water to the tank, and permits thereby the continuous working of the motor. As soon as the water is permitted to flow through the outlet-opening or 75 openings in the bottom of said tank, a considerable suction is created on the piston, so that the same is drawn in downward direction until it closes the outlet-opening. By the 80 downward motion of the piston in following the suction exerted on the same, the spring-bar is bent in downward direction until the piston closes the outlet-opening, when the tension of the spring-bar produces its return 85 and the lifting of the piston. It is preferable to apply some weights to the spring-bar, so that the inertia of the weights, in connection with the inertia of the parts, assists in producing larger and comparatively slow vibrations of the spring-bar. As soon as the piston is moved in upward direction by following the motion of the spring-bar, it is again 90 affected by the suction force exerted on the piston, and is then compelled to descend 95 again until it closes the outlet-opening in the bottom of the tank and the spring-bar is returned again. This alternating action of the suction-force on the piston and of the return action of the spring-bar on the same produces 100 a reciprocating motion, while the water flows through the outlet-pipe. This reciprocating

motion may be converted into continuous rotary motion by the transmitting-mechanism described, or by any other suitable mechanism, and imparted to a crank - shaft, from 5 which the power is transmitted to suitable machinery.

It is obvious that in place of one piston, two pistons or a plurality of pistons may be used, or that the shape of the plug may be 10 changed to a conical valve fitting into the outlet-opening, or it may be made in the shape of a piston which moves in the cylinder of the outlet-pipe, or any other construction may be used. The tank may be made open or with 15 a closed top, when the water may be supplied to it under pressure, in which case the motion-transmitting piston - rod passes through a stuffing - box in the top of the tank. The spring used may be either a bar-spring or a 20 spiral spring, or any other suitable spring. By making the piston of rubber, a better and less hammering action is obtained than when it is made of metal, as such pistons have a greater degree of elasticity and at the same 25 time tend to spring back when they are struck on the bottom of the tank, so as to co-operate thereby with the spring-bar in its upward reaction of the piston.

Having thus described my invention, I 30 claim as new and desire to secure by Letters Patent—

1. The combination, with a tank provided

with a supply-pipe and with an outlet-opening and a discharge-pipe in the bottom of the same, of a piston located at such a distance 35 from the outlet-opening as to be acted upon by the suction caused by the outflowing water, a spring supported above the outlet-opening and connected to the piston so as to produce by the alternating suction-force exerted on 40 the piston and the action of the spring a reciprocating motion, and a power-transmitting device connected with the spring, substantially as set forth.

2. The combination, with a tank and a supply-pipe for the same, said tank being provided with an outlet-opening and a discharge-pipe, of means for producing a partial vacuum in the outlet-pipe, a piston arranged above the outlet-opening in the bottom of the tank 50 at such a distance therefrom as to be acted upon by the suction caused by the outflowing water, a spring supported above the tank, means for connecting the piston with said spring, and a power transmitting device connected with the spring, substantially as set forth.

In testimony that I claim the foregoing as my invention I have signed my name in presence of two subscribing witnesses.

ALBERT GERSTENDÖRFER.
